UNITED STATES PATENT OFFICE.

WILLIAM M. KELLY, OF WESTFIELD, NEW JERSEY.

TYPE.

Application filed August 4, 1923. Serial No. 655,628.

To all whom it may concern:

Be it known that I, WILLIAM M. KELLY, a citizen of the United States, and resident of Westfield, Union County, State of New Jersey, have invented certain new and useful Improvements in Type, of which the following is a specification.

This invention relates to printing apparatus and particularly to an arrangement 10 which is of special utility in connection with large display type.

The manufacture of type of this kind, say 24 point size and upwards, requires considerable metal which is costly and on account of its weight and size the shipment, handling and storage of such type also involves a great deal of expense. The present invention aims to overcome these difficulties by providing an arrangement in which the 20 type characters are formed on relatively thin type plates which plates are adapted to be mounted on a support formed of a plurality of independent metal strips, such as the ordinary slugs and leads. Such thin 25 type plates require much less metal than ordinary type and are therefore less expensive to manufacture and transport and they can be stored in less space and, without involving great loss, can be used once and 30 thrown into the scrap. The slugs and leads employed to form the support are standard parts in printing shops and may be used indefinitely.

The various advantages of the invention 35 will more fully appear from the following specification taken in connection with the accompanying drawings forming a part thereof and in which:

Figure 1 is a perspective view showing 40 two type plates mounted on a base or support made up of four strips, the type illustrated in this figure being a 48 point type and the support being made up of four slugs 12 points in thickness;

Figure 2 is a similar view showing a 36 point type, the base being formed of two inner slugs 12 points in thickness and two outer slugs 6 points in thickness; and.

Figure 3 is a perspective view of an arrangement similar to that shown in Figure 2 illustrating the manner of separating the supporting strips or slugs of the base to replace or insert a new type plate.

Referring to the drawings in detail, 10 55 represents the type plates each of which is provided on the top face with a suitable

character 11, and on the bottom face with a rib 12 preferably of dove-tailed form. These plates may be made relatively thin and light, it being only necessary that they be of sufficient thickness to form a fairly strong and rigid foundation for the characters and for the ribs 12. Such plates may also be made of any size desired, the invention as already noted being particularly designed 60 for large display type of 24 point size or larger.

In forming the base or support for the type plates 10 a plurality of metallic strips are employed. These strips are preferably 70 the ordinary slugs and leads of standard size and thickness. Thus in Figure 1 there is illustrated a 48 point type, the base being made up of four slugs 13, each 12 points in thickness. In Figures 2 and 3 a 36 point type 75 is shown, the base being formed of two inner slugs 13 each 12 points in thickness, and two outer slugs 14 each 6 points in thickness. By employing a sufficient number of slugs and leads a base may thus be built up to 80 support and completely underlie type plates of any size. It will be understood that the type plates are made of such size that the base for the same can be built up from slugs and leads of standard thickness and 85 that the top and bottom edges of the type plates, regardless of the size of characters on the plates, will preferably lie flush with the sides of the base. In other words the length of the type plates is such that the 90 combined thickness of the standard strips forming the base may if desired be made exactly equal to such length. In order to receive the ribs 12 on the bottom face of the type plates 10 it will be seen that the slugs 95 or some of them are provided along at least one edge with a notch or recess 15. Preferably such notches are made only in the 12 point slugs. When two of the notched slugs are placed together as illustrated in 100 the drawings, the two adjacent notches 15 form a dove-tailed recess for receiving the ribs 12 on the type plates 10.

From the foregoing it will be understood that a line of type may thus be set up by 105 assembling the necessary type plates upon a base. The type plates 10, together with the base, make a body which is type high and which can thus be used in an ordinary printing press. When a plurality of lines thus 110 made up are assembled in a holder and locked up each line presses against adjacent

lines so that the slugs and leads forming the base are firmly held in position. The notches 15 of the slugs are made of such size as to closely and accurately fit the ribs 12 so that when a form is locked up in a holder the type plates are held rigidly and in perfect alignment. With an arrangement of this kind it is apparent that in order to change a character in a line it is only necessary to separate the parts of the base as illustrated particularly in Figure 3 when one character may be taken out and another substituted therefor without disturbing the adjacent characters.

15 The foregoing arrangement possesses numerous advantages which will be apparent to those skilled in the art. The manufacture of type plates 10 involves less expense than the ordinary large type-high 20 type and much less expense is involved in the shipment and storage of the same. The type plates being comparatively cheap they may be thrown into the scrap after use thus making it unnecessary to store the same. 25 The slugs and leads used to form the base are not connected in any way so that they can be separated when desired to permit changing a type plate without disturbing the adjacent plates.

30 Having thus described the invention what is claimed as new and desired to be secured by Letters Patent is:

1. A printing arrangement comprising, in combination, relatively thin type plates each 35 having a character on one side thereof and a rib on the other side, a base for said plates comprising a plurality of separate and unconnected metal strips of standard thickness

used in printing arranged beneath said plates and completely underlying the same, 40 the combined thickness of said strips being equal to the length of said plates whereby the ends of said plates are flush with the sides of said base, two of said strips having notches along one edge thereof which cooperate to form a groove to receive and tightly clamp the ribs on said type plates and hold the same in position when the arrangement is locked up in a holder; said strips and type plates together forming an 50 arrangement which is of standard type height.

2. A printing arrangement comprising in combination, relatively thin type plates each having a character on one side and a rib 55 on the other side, a base for said plates comprising two strips of standard thickness used in printing arranged beneath said plates and having notches along one edge thereof which cooperate to form a groove 60 to receive and tightly clamp the ribs on said type plates and hold the same in position when the arrangement is locked up in a holder, said base also comprising two additional strips arranged one on either side of 65 said first named strips and beneath said plates, all of said strips being entirely separate and disconnected, whereby the same may be separated and individual type plates removed or inserted without disturbing adjacent plates; said strips and type plates together forming an arrangement which is of 70 standard type height.

In testimony whereof I hereunto affix my signature.

WILLIAM M. KELLY.
